UNITED STATES PATENT OFFICE.

WILFRED A. BEAUCHAMP AND WILLIAM W. DARROW, OF CHICAGO, ILLINOIS, AS
SIGNORS TO CAMEL COMPANY, OF CHICAGO, ILLINOIS, A CORPORATION OF ILLI-
NOIS.

SECURING MEANS.

Application filed December 11, 1925. Serial No. 74,705.

The present invention relates to securing means.

More particularly the present invention relates to means for securing the sliding doors of railway freight cars. The problem of protecting the contents of railway cars against thieving is a very difficult one, inasmuch as thieves display great ingenuity in making their way into the interior of the cars. Drastic laws have been put on the statute books to deter thieves from destroying the sealing ribbons which are in common use for sealing the doors against opening. Though said sealing ribbons are quite 10 flimsy, the fact that the unauthorized destruction of same carries with it very drastic penalties has deterred thieves from tampering with said sealing ribbons and has driven said thieves to the use of expedients 15 for effecting entrance to the cars without destroying said sealing ribbons.

The securing means should be sturdy and simple in construction and should present no parts which are liable to become loose 20 from the car and to be mislaid. Structure which has proven efficient in service is illustrated in the patent to Devine No. 933- 25 632, but said structure is not adapted to be riveted in position and therefore it is not adapted for steel freight cars. The structure shown in said Devine patent has other 30 faults which are obviated by the present invention.

An object of the present invention is to 35 provide securing means which is simple and sturdy and which adapts itself to be riveted to the steel structure of a railway car.

A further object is to provide locking 40 means involving a reciprocable bolt which bolt cannot be removed after the securing means has been secured in place on the side of a car.

A further object is to provide an improved securing means made up of members 45 which are simple to fabricate and assemble, which cannot be disassembled while in position upon a car and which are simple in operation.

Further objects will appear as the de- 50 scription proceeds.

Referring to the drawings—

Figure 1 is a view in side elevation of one

embodiment of the present invention attached to the side of a railway freight car;

Figure 2 is a sectional view taken along the plane indicated by the arrows 2—2 of Figure 1;

Figure 3 is a sectional view taken along the plane indicated by the arrows 3—3 of Figure 1;

Figure 4 is a view illustrating the manner of inserting the bolt within the keeper housing before said keeper housing has been attached to the side of the car; and

Figure 5 is a perspective view of a bolt forming part of the present invention.

In Figure 3 the side of the car is indicated as a steel member, whereas in Figures 1 and 2 the side of the car is indicated as a wooden member. Figures 1 to 3 illustrate the fact that the present invention is applicable not only to cars having steel sides but to the older type of cars as well.

The numeral 1 indicates a car side, and the numeral 2 indicates a sliding door. In the illustrated embodiment of the present invention the side 1 of the car takes the form of an auxiliary door such as is used with cars intended for carrying relatively bulky lading, such as automobiles and machinery, the side 1 being provided with the door jamb 3. The details of the side 1 and the door jamb 3 are not involved in the present invention and further description of same is unnecessary. It will be sufficient

to state that the door 2 is adapted to have sliding relationship with the side 1 in substantially the same plane as said side 1. Secured to the sliding door 2 is the hasp retainer 4, which may be bolted or riveted to the door 2. It will be understood, of course, that means for fastening the hasp retainer 4 upon the door 2 will be so chosen

that they will not permit tampering from the outside of the door. In Figures 1 and 2, bolts 5 are provided for holding the hasp retainer in place, said bolts 5 having rounded heads 6 for preventing tampering. The hasp retainer 4 provides the loop 7 for hinged supporting the hasp member 8.

Secured to the side member 1 is the keeper member 9, which includes the reciprocating bolt 10. Said keeper member 9 is provided with the guide lug 11, the keeper lug 12 and

the sealing lug 13. In the illustrated embodiment of the present invention the guide lug 11 is uppermost, the keeper lug 12 appears below said guide lug, and the sealing lug 13 is lowermost of the three.

The keeper member 9 is adapted to be secured against the outer face of the side 1 of the car and is provided with the bed portion 14, which in the illustrated embodiment of the present invention provides four holes for the reception of rivets or bolts, or other preferred holding means. In the construction shown in Figures 1 and 2, bolts 15 are provided having round heads presented exteriorly of the car, whereby to prevent tampering by thieves. In the structure shown in Figure 3, rivets 15' are provided for holding the keeper member 9 in fixed position upon the exterior face of the side member 1 of the car. The keeper lug 11 is slotted for the reception of the bolt 10, and the bed portion 14 of the keeper member 9 is cut away beneath the guide lug 11 in order to permit the insertion and withdrawal of the bolt 10 before the keeper member 9 is attached in position on the side of the car. The lower wall 15" of said cut away portion provides a seat for the lower extremity of the bolt 10 under certain conditions to be referred to hereinafter.

Referring particularly to Figures 4 and 5, it will be noted that the bolt member 10 comprises an elongated member having a hook portion 16 at one end. The rear of the bolt 10 is provided with a rearwardly extending portion 17, which in service is adapted to abut against the car side 1 and prevent the removal of the bolt 10 from the guide lug 11. Said rearwardly extending portion 17 preferably takes the form of a flat web disposed in the plane of the hook portion 16, being of the same thickness as the shank of the bolt 10. This enlarged portion prevents prying of the bolt in a direction transverse to the car side. The lower extremity of the bolt 10 is provided with the portion 18, thickened laterally of the bolt 10. Said laterally thickened portion 18 effectually prevents the bolt 10 from being withdrawn upwardly through the guide lug 11, the aperture in said guide lug 11 being of only sufficient width to permit the free passage of the narrower portions of the bolt 10. The keeper lug 12 is recessed, as indicated by the numeral 19 in Figure 2, to permit the passage of the enlarged portion 18 of the bolt 10, but is provided with the shoulders 19-19 adapted to abut against the side of the bolt 10 to prevent swinging movement of said bolt 10 in a plane parallel to the side of the car. The thickened portion 18 of the bolt 10 and the sealing lug 13 are provided with slots 20 adapted to receive a sealing ribbon.

Progressive positions assumed by the bolt 10 while said bolt is being inserted within

the guide lug 11 are indicated by the numerals 21, 22, 23 and 24 in Figure 4, it being assumed, of course, that the keeper member is free from the side of the car.

The hook portion 16 of the bolt 10 is inserted within the guide lug 11 in the manner indicated by the numerals 21 and 22. Said bolt 10 is then raised relative to the guide lug 11 to a position approximating that indicated by the numeral 23 of Figure 4, after which said bolt 10 is allowed to drop to the position indicated by the numeral 24 of Figure 4. The keeper member 9 with the bolt 10 mounted therein may be readily mounted upon the side of a car and secured thereto by means of the bolts 15 or the rivets 15'.

When the keeper member 9 is located in position on the side of the car, it will be impossible to withdraw the bolt 10 from the keeper member 9 by reversing the movements described above for inserting said bolt 10 in position. Such a reversal in movement will be prevented by reason of the engagement of the rearwardly extending portion 23 of the bolt 10 with the side of the car. Removal of the bolt vertically from the keeper member 9 will also be prevented by reason of engagement of the thickened portion 18 with the guide lug 11.

In service, when it is desired to hold the bolt 10 up out of cooperative relationship with the hasp member 8 and the keeper lug 12, said bolt will be disposed with the lower extremity thereof resting upon the wall 15" defining the cut away portion in rear of the guide lug 11. At this time the bolt 10 will assume the position indicated in dotted lines in Figure 3.

The hasp 8, assuming the door 2 to be in closed position, may be moved into cooperative relationship with the keeper lug 12, after which the bolt 10 may be allowed to drop to the position shown in full lines in Figure 3, that is—to a position within the keeper lug 12 and in abutting relationship with the hasp member 8. As indicated above, the contour of the keeper lug 12 is such as to prevent swinging movement of the bolt 10 in a plane parallel with the side of the car. A sealing ribbon may be inserted through the cooperating slots 20 of the sealing lug 13 and the thickened portion 18 of the bolt 10.

It should be noted that according to the present invention the bolt 10 cooperates with three rigid abutments, namely, the guide lug 11, the keeper lug 12, and the sealing lug 13. By reason of these three abutments a very efficient sealing effect is had. By reason of the fact that the bolt 10 is held by the lugs 11 and 12 against movement in a plane parallel with the side of the car, the sealing ribbon may be inserted through the slot 20 of the bolt 10 and through the cooperating aperture of the sealing lug 13,

producing a lock which will effectually baffle the attempts of thieves to tamper therewith.

The present invention is made up of simple parts which are simple to manufacture and which may be made very sturdy. The assembly of said parts is very simple, and when once assembled upon the side of a car there is nothing to come loose and nothing to become lost. The bolt 10 may be disposed out of the way of the keeper lug 12 when not in use, thereby simplifying the matter of closing and securing the door 2.

Though the preferred embodiment of the present invention has been described in detail, it will be clear that many modifications will occur to those skilled in the art. It is intended to cover all such modifications that fall within the scope of the appended claims.

What is claimed is—

1. In combination, a wall member, a door member, a hasp pivoted to one of said members and a keeper secured to the other of said members, said keeper being provided with a reciprocable bolt, a keeper lug for receiving said hasp and said bolt, and a guide lug for receiving said bolt, said keeper being open in rear of said guide lug, said bolt being provided with an enlarged end portion for preventing removal thereof through said guide lug and having a hook portion cooperating with said guide lug and an enlarged portion in rear of said hook portion adapted to cooperate with said guide lug and with the member upon which said keeper is attached for preventing the removal of said bolt, said enlarged portion comprising a web for strengthening said bolt in the plane of said hook portion.

2. In freight car construction, in combination, a wall member, a door member cooperating therewith, a hasp pivoted to one of said members, a keeper secured to the other of said members, said keeper including a reciprocable bolt, said keeper being provided with a keeper lug for receiving said bolt and said hasp, and a guide lug provided with an open-ended slot adapted to be closed by said member upon which said keeper is mounted, said bolt being provided with an enlarged end portion for preventing removal thereof through said guide lug and having a hook portion and an enlarged portion disposed rearwardly of said hook portion for cooperating with said last mentioned member for preventing the removal of the hook portion of said bolt through said slot, said enlarged portion comprising a web for strengthening said bolt in the plane of said hook portion.

3. Securing mechanism comprising a keeper having a bed portion adapted to be secured to a flat surface, said keeper member being provided with a reciprocable bolt

and with a guide lug, a keeper lug and a seal lug projecting from said bed portion, said bolt being provided with an enlarged end portion for preventing the removal of said bolt from said keeper lug in one direction, said guide lug being provided with an open-ended slot, said bolt being provided at its other end with a hook portion and an enlarged portion rearwardly of said hook portion for permitting the insertion of said hook portion through said slot when said bed portion is free from said flat member but for preventing the removal of said hook portion when said slot is closed by said flat member.

4. A keeper comprising a metal casting having a bed portion adapted to be backed up against a flat member, said keeper including a reciprocable bolt, a guide lug having a slot open through said bed portion for receiving said bolt, a keeper lug providing an eye for receiving said bolt and also adapted to receive a hasp, and a seal lug adapted to cooperate with the lower extremity of said bolt, said bolt having its lower extremity enlarged to such an extent as to prevent the removal thereof through said guide lug, said bolt having at its other extremity a hook portion and an enlarged portion disposed rearwardly of said hook portion adapted to be inserted through said slot when said keeper is free from adjacent objects, but of sufficiently large dimensions to prevent the removal of said hook portion through said slot when said bed portion is backed up against a flat member.

5. A keeper comprising a casting having a bed portion adapted to be backed up against a flat member, said keeper including a reciprocable bolt, a guide lug having a slot therein for receiving said bolt, and a keeper lug providing an eye portion adapted to receive said bolt and a hasp, said slot being open at the rear of said keeper, said bolt comprising a flat member having a laterally widened portion at one extremity of sufficiently great dimension to prevent the removal thereof through said slot, said bolt having at its other extremity a hook portion and an enlarged portion rearwardly thereof adapted to be inserted into said slot when said keeper is free of adjacent objects, said hook portion and said enlarged portion being sufficiently great in dimensions to prevent the removal thereof from said guide lug when the rear of said slot is closed.

6. A keeper comprising a casting having a bed portion adapted to be backed up against a flat member, said keeper including a reciprocable bolt, a guide lug having a slot therein for receiving said bolt, and a keeper lug providing an eye portion adapted to receive said bolt and a hasp, said slot being open at the rear of said keeper, said bolt comprising a flat member having a lat-

erally widened portion at one extremity of sufficiently great dimension to prevent the removal thereof through said slot, said bolt having at its other extremity a hook portion and an enlarged portion rearwardly thereof adapted to be inserted into said slot when said keeper is free of adjacent objects, said hook portion and said enlarged portion being sufficiently great in dimensions to prevent the removal thereof from said guide

lug when the rear of said slot is closed, said bed portion being provided with a shoulder adjacent to said slot for receiving and holding said bolt out of obstructing relationship with said keeper lug.

15

Signed at Chicago, Illinois, this 7th day of December, 1925.
